(57) **CLAIM**

The ornamental design for a filter capsule as shown and described.

DESCRIPTION

FIG. 1 is a bottom isometric view of a filter capsule of the present invention shown in a first embodiment.

FIG. 2 is a top isometric view thereof.

FIG. 3 is a front view thereof.

FIG. 4 is a rear side view thereof.

FIG. 5 is a right side view thereof.

FIG. 6 is a left side view thereof.

FIG. 7 is a top view thereof.

FIG. 8 is a bottom view thereof.

FIG. 9 is a bottom isometric view of a filter capsule of the present invention shown in a second embodiment.

FIG. 10 is a top isometric view of the filter capsule shown in FIG. 9.

FIG. 11 is a front view of the filter capsule shown in FIG. 9.

FIG. 12 is a rear view of the filter capsule shown in FIG. 9.

FIG. 13 is a right side view of the filter capsule shown in FIG. 9.

FIG. 14 is a left side view of the filter capsule shown in FIG. 9.

FIG. 15 is a top view of the filter capsule shown in FIG. 9.

FIG. 16 is a bottom view of the filter capsule shown in FIG. 9.

FIG. 17 is a bottom isometric view of a filter capsule of the present invention shown in a third embodiment.

FIG. 18 is a top isometric view of the filter capsule shown in FIG. 17.

FIG. 19 is a front view of the filter capsule shown in FIG. 17.

(Continued)

FIG. 20 is a rear view of the filter capsule shown in FIG. 17. FIG. 21 is a right side of the filter capsule shown in FIG. 17. FIG. 22 is a left side view of the filter capsule shown in FIG. 17. FIG. 23 is a top view of the filter capsule shown in FIG. 17; and, FIG. 24 is a bottom view of the filter capsule shown in FIG. 17. The broken lines in the drawings depict portions of the filter capsule that form no part of the claimed design.
